UNITED STATES PATENT OFFICE.

ADOLPH H. SOMMERS, OF ALLENTOWN, PENNSYLVANIA.

HEEL.

1,340,571.

Specification of Letters Patent. Patented May 18, 1920.

Application filed January 2, 1920. Serial No. 348,910.

To all whom it may concern:

Be it known that I, ADOLPH H. SOMMERS, a citizen of the United States, and a resident of Allentown, in the county of Lehigh and 5 State of Pennsylvania, have invented a new and useful Improvement in Heels, of which the following is a specification.

My invention relates to heels and more particularly to fastening means for effecting 10 securing the heel to the shoe.

An important object of my invention is to provide fastening means of this character which will be especially adapted for use with ladies' high-heel shoes and which will 15 effectively and positively secure the heel to the shoe and prevent breaking away of the heel from the sole at the point of attachment or of the plies of the heel from each other adjacent this point.

Another object of the invention is to provide 20 a fastening means of this character of strong and durable construction, easily applied and inexpensive to manufacture.

Other objects and advantages reside in the 25 certain novel features of the construction, arrangement and combination of parts which will become apparent as the description proceeds, reference being had to the accompanying drawing, in which—

Figure 1 is a perspective view of my improved fastening means,

Fig. 2 is a rear elevational view of the same,

Fig. 3 is a vertical sectional view showing 35 my fastening means applied,

Fig. 4 is a vertical sectional view showing a modified form of fastening means applied,

Fig. 5 is a rear elevation of the modified 40 form of fastening means.

Referring to the drawings it will be seen my invention contemplates a shoe indicated generally at 10 and including a sole 11 and a heel 12 attached to the sole by cement, 45 pegs or the like. As shown, the heel 12 is of the high-heel type. 13 indicates the line of attachment of the heel to the sole and 14 and 15 the lines between the plies of the heel adjacent the point of attachment.

In practice it has been found that due to 50 the shape of the high-heel and its relation to the shoe and to the weight of the wearer, that the strain at the rearmost point of attachment, that is, to the rear of the heel 55 along the lines 13, 14 and 15, is of such

moment as to break away the heel from the shoe or to break away the plies of the heel from each other adjacent this point, despite the cement, pegs or other fastening means now employed.

To overcome and remedy this difficulty I provide an improved fastening means positioned at the point where the moment of the strain is the greatest and preferably provide a countersink therefor, as indicated at 60 16 in Fig. 4. The fastening means comprises a body portion 17 adapted to be seated in the countersink 16 and an integral downwardly extending double-prong 18 adapted to be engaged over the sole 11, and an integral upwardly extending prong 19 at its 65 lower end adapted to be driven into the body of the heel. Between the upper and lower prongs 18 and 19, an intermediate inwardly extending prong 20 is formed preferably by 70 stamping or punching the same from the body portion 17. The prong 20 also enters the body of the heel.

The region of the engagement of the 75 prong 19 with the body of the heel is below 80 the point where the moment of the strain is so great as to tend to cause the plies of the heel to break away from each other.

In the forms of my invention shown in 85 Figs. 4 and 5, the body portion of the fastening means is solid and unbroken and the middle prong 20 is dispensed with. The body portion in this form is tapered from the upper to the lower end as shown in Fig. 5. This form of fastening means is in all 90 other respects like the preferred form and is positioned in precisely the same manner, as shown in Fig. 4.

As previously described the fastening means is seated in a countersink as shown in 95 Fig. 4 but, if desired, the countersink may be dispensed with and fastening means applied directly to the rear face of the heel as shown in Fig. 3. The outer face of the body portion is colored to correspond with the color 100 of the heel and blends with the same, so as to escape the notice of the ordinary observer.

In practice, the fastening means may be applied when the shoe is manufactured, but preferably it is not applied until the heel 105 breaks away from the sole or the plies of the heel adjacent the sole break away from each other or these parts show a tendency to this action. When this occurs the countersink is formed in the heel and the fastening means 110

pressed or driven into position by any suitable tools, while the parts of the shoe are held in their proper position. After the fastening means has been driven home the parts 5 of the shoe are effectively and positively maintained in proper position, strain being taken through the fastening means to the sole, the part best adapted to bear the same.

I claim:—

- 10 1. In a device of the character described, the combination with a shoe including a sole and a heel attached thereto having a countersink in its rear face adjacent the point of attachment to the sole, of fastening means 15 consisting of a body portion adapted to be seated in the countersink of said heel, a downwardly extending prong at the upper end of said body portion adapted to engage the sole, an upwardly extending prong at 20 the lower end of said body portion adapted to engage the heel and an intermediate prong adapted to engage the heel.

2. In a device of the character described, the combination with a shoe including a sole 25 and a heel attached thereto, of fastening means for securing the heel to the sole disposed at the rearmost point of attachment and consisting of a body portion, a downwardly extending prong at its upper end

engaging the sole, an upwardly extending 30 prong at its lower end engaging the heel and an intermediate prong engaging the heel.

3. In a device of the character described, the combination with a shoe including a sole and a heel attached thereto, of fastening 35 means securing the heel to the sole disposed at the rearmost point of attachment and consisting of a body portion, an upper prong engaging the sole, a lower prong engaging the heel, and an intermediate prong engag- 40 ing the heel.

4. In a device of the character described, the combination with a shoe including a sole and a heel attached thereto, of fastening 45 means securing the heel to the sole disposed at the rearmost point of attachment and consisting of a body portion, an upper prong engaging the sole and a lower prong engag- 50 ing the heel.

5. In a device of the character described, 55 the combination with a shoe including a sole and a heel attached thereto, of fastening means securing the heel to the sole disposed at the rearmost point of attachment and consisting of a tapered body portion, an upper prong 55 engaging the sole and a lower prong engaging the heel.

ADOLPH H. SOMMERS.
